JAMES D. BRYSON AND ALONZO POTTER, OF NEW CASTLE, PENNSYLVANIA.

Letters Patent No. 79,442, dated June 30, 1868.

IMPROVED SPIKE-MACHINE.

The Schedule referred to in these Letters Patent and making part of the same.

TO ALL WHOM IT MAY CONCERN:

Be it known that we, JAMES D. BRYSON and ALONZO POTTER, of New Castle, in the county of Lawrence, and State of Pennsylvania, have invented a new and improved Machine for Making Railroad-Spikes; and we do hereby declare that the following is a full, clear, and exact description of the construction and operation of the same, reference being had to the annexed drawings, making a part of this specification, in which--

Figure 1 is a longitudinal vertical section through the line $x x$ of fig. 2.

Figure 2 is a top view.

In this invention a new device is employed for cutting off the rod before the point of the spike is formed, and an attachment is used to guide and carry the end of the rod to the die, an operation which has hitherto been performed by hand, and in an inconvenient and exceedingly imperfect manner.

In the drawings, A represents the frame of the machine, and B the horizontal table or platform on its front side, on which the iron rod from which the spikes are to be formed, lies during the operation of the machine. C is the main shaft, provided with a fly-wheel, D, and E is the mould, in which the spike is formed. The rod, shown in red lines in fig. 2, is laid on the table in the position there represented, and the end of it is thrust by the operator into the mould E. The moment it reaches the proper position, a cam, d, on the fly-wheel, forces a sliding cutter, F, against it and severs it, leaving the part that is to form the spike in the mould. As soon as the rod is severed, the cam d releases the sliding cutter, which is instantly retracted by a spring, e. As soon as the sliding cutter is out of the way, the dies G and H that form the side and top of the spike are actuated from the main shaft by means of cams g and h, and levers g' and h', respectively, and together shape and "point" the body of the spike. As soon as they have performed their office, the header I, operated by a cam, i, and lever J, forms the head of the spike. K is a sliding plate, working on the table B, and actuated by a cam, k, and lever L, which now moves forward, and by a projecting arm, m, forces the spike out from the mould, causing it to drop into a receptacle prepared for the purpose. The slide K is provided with another arm n, shorter than the first arm by about the width of a spike, which, as soon as the arm m has removed the old spike, pushes sideways the end of the rod that was cut off, bringing that end directly in front of the mould, so that the operator, by simply shoving the rod forward, causes it to assume the proper position for another cut, to make another spike. O is an upright plate, between the two arms m and n, which guides and steadies the motion of the plate K, and affords an abutment to guide the rod also when moving back to its place in front of the dies, preparatory to the forming of a new spike. It is made of steel, and provided with a sharp square edge, o, which assists the cutter F in severing the rod.

It will be observed that the arm n has an upright flange or lip, n', which sets firmly against the side of the rod while the cutter is acting against the latter, holding the rod firmly in place during the operation of severing it, and causing a clean, straight cut, without the bending of the rod at that point, which invariably takes place in all other machines, and which injures the rod so much as frequently to prevent the next spike from being formed perfectly.

The sliding plate K, with its arms m and n, is designed to obviate a very great difficulty that has been found to exist in machines for this purpose hitherto in use. In none of these machines has there been any attachment for guiding the end of the rod to place after it was cut off, but that operation has been left to be performed by hand, and usually trusted to boys. The result has been that the operators frequently fail to bring the end of the rod to the proper position in season to get it under the dies, and a whole revolution of the shaft is thus lost, the operator having to wait and try again at the next revolution. And again, if by any means the old spike were not pushed out, the operator could not see it, and unmindful of the fact, he pushed the rod into place while the old spike was yet in position, and thereby the machine was broken. Such accidents are of frequent occurrence with the machines hitherto in use. With this, however, such an accident cannot occur, for if from any cause the old spike should not be removed, the arm m will come in contact with it, and will be arrested in its forward motion, thereby stopping the plate K and the arm n, and consequently not bringing the rod to its place in front of the dies, so that as long as the old spike remains in place, the rod will not be moved.

When the plate K has pushed the spike out of its bed or mould, and has brought the end of the rod into position to be readily thrust into place and again cut off for a new spike, it is at once retracted by the action of a spring, k. a is a spring, which retracts the die G, and a' is another, which retracts the die H. The heading-die I may be retracted by an independent spring, or by a shoulder, r, on the side of the die H, as seen in the drawings.

It will be observed that in forming the spike, the iron will, by compression, be elongated, so as to occupy more space than before the dies operate upon it, and inasmuch as the heading-die prevents any elongation of the spike in that direction, the whole of the elongation must take place at the point, which will be thrust forward a little beyond the place where it was severed from the rod. The die H must therefore be made to project a little in front of the plate O, as seen at t, in order to operate upon every part of the elongated spike. But when thus projecting, said shoulder prevents the operating of the cutter F at the same time with the die H, inasmuch as were the die not out of the way when the cutter performed its operation, the effect would be that the shoulder t would be cut off instead of the iron rod. To prevent this, therefore, we construct our machine in such a manner that the cutter first operates, and is then retracted entirely out of the way, immediately after which the dies G, H operate, and then the header completing the spike, when the plate K pushes it out of the way, and brings the rod into position for a new cut. The whole operation of the machine is therefore exceedingly simple and perfect. It has been thoroughly tested on a large scale in the manufacture of spikes, and has been found to do the work in a superior manner.

Having thus described our invention, what we claim as new, and desire to secure by Letters Patent, is—

1. The sliding plate K; when provided with the arms m and n, or their equivalents, in combination with cutter F and guide O, all arranged and operating in the manner and for the purpose set forth.
2. A slide or sliding arm n, arranged on the bed of the machine, as described, in combination with its operative mechanism, for the purpose of moving the rod to position, substantially as described.

JAS. D. BRYSON,
ALONZO POTTER.
